ATTORNEY.

UNITED STATES PATENT OFFICE.

LOUIS V. LUCIA, OF HARTFORD, CONNECTICUT, ASSIGNOR TO THE FULLER BRUSH COMPANY, OF HARTFORD, CONNECTICUT, A CORPORATION OF CONNECTICUT.

DISH MOP.

Application filed August 25, 1922. Serial No. 584,252.

To all whom it may concern:

Be it known that I, LOUIS V. LUCIA, a citizen of the United States, and a resident of Hartford, in the county of Hartford and State of Connecticut, have invented new and Improved Dish Mops, of which the following is a specification.

My invention relates to the class of hand implements used for cleaning dishes and similar articles, and an object of my invention, among others, is the production of a device of this class that shall be particularly efficient in the results obtained by its use, and also that shall be extremely simple in construction and that may be produced at a minimum cost.

One form of my improved dish mop, in the construction and use of which the objects herein set out, as well as others, may be attained, is illustrated in the accompanying drawings, in which—

Figure 1 is a view in front elevation of my improved dish mop.

Figure 2 is a side view of the same.

Figure 3 is a detail view partially in section illustrating the means for securing the brush shank to the handle, the shank being shown in position just before being engaged by the handle.

Figure 4 is a view similar to Figure 3 but showing the brush shank engaged with the handle and secured thereto.

My invention contemplates the construction of a dish mop having a core or base composed of wire usually embodying two strands twisted together, and within the twists or turns of which the mop material, as coarse cotton threads, is secured in the operation of twisting the wire strands, it being my purpose to so form this structure that a particularly heavy body of said material shall be so disposed as to secure most satisfactory results in the use of the mop.

In effecting such purpose the mop material is secured to the core, beginning at a point some distance from one end and extending to the opposite end, the uncovered part of the core comprising a shank 6. The mop material projects from the core on all sides, comprising a heavy body completely

enveloping the core, and the latter, as to the part containing the mop material, is bent into curved form, preferably that of a circle, and of such size that the material completely fills the center of this curved part, forming a mop head 7.

In constructing this head I preferably take a single piece of wire and bend it at the center back upon itself, and twist the two strands thus formed together, the bent end forming the extreme end of the core that is bent around in proximity to or against the main part. The threads comprising the brush material are secured to the core in this twisting operation, and the end is bent into its circular or other curved form preferably after the threads have been secured in place.

The two strands comprising the core are preferably of the same length, or substantially so, the ends thereof being formed with points 8. In forming these points the ends are cut away on one side, or beveled, thus forming a notch 9 between them, and this construction is made use of in securing the shank to the handle, and as shown in Figures 3 and 4 of the drawings. From this it will be seen that when the shank is forced into the hole 10 in the end of the handle 11, the pointed ends, after they enter the material in the bottom of the hole, will be spread apart a distance greater than the diameter of the hole, with a result that the shank will be secured tightly in place and against removal from the handle.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to uses other than those above set out.

I claim—

1. A structure comprising strands of wire twisted together to secure mop material therebetween, the ends of said strands being pointed and beveled in opposite directions

- 2.
- for spreading purposes, and a handle into which said pointed ends are driven with the points embedded in the handle.
2. A structure comprising strands of wire twisted together with mop material therebetween, the ends of said strands being beveled in opposite directions, and a handle having a socket frictionally receiving the ends of the strands with the beveled ends thereof spread apart and entering the body of the handle, and with the terminal portions of the beveled ends assuming a position greater than the diameter of the socket.
3. The method of connecting a mop head having a plurality of twisted strands forming a shank to a handle, consisting in beveling the ends of the strands of the mop head shank, positioning the strands in the socket of a handle with the ends of the strands engaging the bottom wall of the socket, and then moving the strands farther into the handle socket to cause the beveled ends to spread apart and be embedded in the handle laterally of the socket. 15 20

LOUIS V. LUCIA.
